SHEET COUNTER FOR PAPER SHEET
HANDLING MACHINES

Kenneth A. Wagner, Brainerd, Minn.

Application April 8, 1952, Serial No. 281,230

2 Claims. (Cl. 93—93)

1

This invention relates to sheet counters for paper sheet handling machines, such as printing presses or folding machines, and more particularly to an improved rotary counter for a folding machine for marking folded sheets issuing from the machine at intervals of a predetermined number of sheets.

It is among the objects of the invention to provide an improved sheet counting attachment for a sheet folding machine which can be easily mounted thereon without material modification of the machine structure for marking folded sheets issuing from the machine at intervals of a predetermined number of sheets; which rides upon the folded sheets and does not damage them in any way; which accurately counts the sheets as they issue from the folding machine and marks each predetermined numbered sheet so that the sheets can be easily arranged in piles or stacks with the same number of sheets in each stack; and which is simple and durable in construction, economical to manufacture, easy to install, and effective and efficient in operation.

Other objects and advantages will become apparent from a consideration of the following description and appended claims in conjunction with the accompanying drawings wherein:

Figure 1 is a fragmentary top plan view of a paper sheet folding machine showing a sheet counter illustrative of the invention operatively mounted thereon;

Figure 2 is a fragmentary end elevational view of the machine and counter illustrated in Figure 1;

Figure 3 is a cross sectional view on the line 3—3 of Figure 1;

Figure 4 is a cross sectional view on the line 4—4 of Figure 1;

Figure 5 is an enlarged fragmentary side elevational view of a sheet counting element with a portion broken away and shown in cross section to better illustrate the construction of the element;

Figure 6 is a fragmentary cross sectional view on the line 6—6 of Figure 5; and

Figure 7 is a perspective view of a sheet riding roller constituting an operative component of the assembly.

With continued reference to the drawings, the illustrated sheet folding machine, generally indicated at 10, has at its rear or discharge end a substantially horizontally disposed table 11 provided with a longitudinally extending opening of rectangular shape in which an endless con-

2

veyor, generally indicated at 12, is mounted for receiving thereon and moving folded sheets in a direction away from the folding machine.

The conveyor 12 comprises rollers 13 and 14 journaled on the table one at each end of the opening in the table and extending transversely across a portion of the width of the table, and an endless belt 15 of flexible material trained over the rollers and having its upper flight disposed in the opening in the table substantially flush with the surface of the table. At least one of the rollers is driven from the mechanism of the folding machine so that the belt is continuously driven in a direction such that its upper flight 15 moves toward the discharge end of the machine. The belt 15 receives folded paper sheets 16 in partially overlapping relationship, as illustrated in Figure 1, and moves the folded sheets toward the discharge end of the machine to a stacking table 17 disposed at the end of the table 11 remote from the discharge end of the machine 10.

Rails 18 and 19 rise above and extend longitudinally of the table 11 one at each side of the table and a shaft 20 extends transversely across the table across the conveyor 12 at a level above the table and conveyor belt and is supported at its ends on the rails 18 and 19.

The shaft 20 is supported at one end in a bearing 21 on the rail 18 and is supported at its other end in a bearing 22 slidably mounted on a rod 23 which extends longitudinally of the rail 19 on a level above the rail 18 and is secured at its ends to the rail 19 by brackets, as indicated at 24.

Roller arms, severally designated 25, 26 and 27 are pivotally mounted each at one end on the shaft 20 at spaced apart locations along the shaft and extend from the shaft toward the discharge end of the folding machine 10, and rollers 28, 29 and 30 are journaled on the arms 25, 26 and 27, respectively, at locations spaced from the shaft 20 to ride on the upper surfaces of the folded sheets 16 issuing from the machine so as to maintain the stack of partially overlapping sheets in a flat condition.

An arm 31 is mounted on the shaft 20 by a bearing collar 32 connected to the arm and surrounding the shaft at a location adjacent to the inner side of the conveyor 12 and this arm extends substantially perpendicularly from the shaft 20 in a direction away from the discharge end of the machine.

A stub shaft 33 is mounted on the arm 31 and is spaced from the shaft 20 in a direction

away from the discharge end of the machine 10 and is disposed substantially parallel to the shaft 20 and to the table 11.

A disc 35 of substantially circular shape is centrally journaled on the stub shaft 33 over the conveyor 12 adjacent to the inner edge of the latter. This disc 35 is provided around its periphery with a series of teeth 36 which are all of substantially the same size and are inclined in the same direction relative to related radii of the disc. There are a predetermined number of the teeth 36 corresponding to the number of folded sheets which it is desired to assemble in each separate stack of sheets. The disc is provided with a radially disposed bore 37 extending inwardly of the disc from the pointed outer end of one of the teeth 36, an aperture 38 being provided through the disc at the inner end of the bore 37. A marking element 39, such as a soft pencil or crayon lead, is frictionally mounted in the bore 37 with its outer end exposed beyond the outer pointed end of the corresponding tooth 36 and with its inner end disposed within the aperture 38 so that the lead can be adjusted outwardly of the disc as its outer end is worn down.

The disc teeth 35 are so inclined that as a stack of overlapped folded sheets 16 issues from the machine and is carried along upon the conveyor 12, the forwardly disposed, exposed edge of each sheet engages a tooth 39 of the disc and rotates the disc through such an angle that the forward edge of the next succeeding sheet will engage the next succeeding tooth of the disc. The disc is thereby rotated by engagement of succeeding teeth by the succeeding edges of sheets of the stack issuing from the machine. Each time a tooth adjacent to the marking element 39 is engaged by a sheet, a mark is made on the edge of the sheet and the sheets spaced apart at intervals of a predetermined number of sheets are thus marked as the overlapped sheets issue from the machine.

Washers 40 and 41 are mounted on the stub shaft 33 one at each side of the disc 35, and a nut 42 is threaded onto the stub shaft at the side of the disc 35 remote from the arm 31 and bears against the washer 40. A lock nut 43 is also threaded onto the shaft and bears against the nut 42 so that the nuts 42 and 43 are locked on the stub shaft. Clamp nuts 44 and 45 are threaded onto the shaft between the disc 35 and the arm 31 in opposed relationship to each other and a compression spring 46 surrounds the stub shaft between the clamp nut 44 and the washer 41, so that the washer 40, the disc 35, and the washer 41 are compressed together. This arrangement acts as a friction brake for the disc 25, resisting free rotation thereof and insures that the only rotation of the disc is that imparted to it by the engagement of the edges of the sheets 16 with the teeth of the disc.

A lever 48 is disposed between the clamp nuts 44 and 45 and has an elongated slot therein receiving the stub shaft 33. A roller 50 is journaled on one end of the lever 48 and bears on the folds of the overlapped paper sheets 16 near the disc 35 to maintain the paper sheets in a flat condition and prevent the folds thereof from curling upwardly when they contact the teeth of the disc 35. The pressure of the roller 50 on the paper sheets can be adjusted by moving the lever 48 longitudinally thereof relative to the stub shaft 33 and clamping the lever in adjusted position by tightening the clamp nuts 44 and 45 toward each other.

A rigid arm 51 extends upwardly from the shaft 20 adjacent to the bearing collar 32, and a contractile coil spring 52 is connected at one end to the arm 51 at the upper end thereof and is connected at its other end to the stub shaft 33 at a point adjacent to the arm 31. The spring 52 acts to prevent excessive pressure of the disc 35 upon the paper sheets 16 issuing from the sheet handling machine. The arm 31 may be one of the roller arms 25, 26 and 27 carrying the sheet flattening rollers 28, 29 and 30, such arm being merely rotated through an angle of 180 degrees so that it extends rearwardly from the shaft 20 instead of forwardly from this shaft. In such case, the sheet flattening roller of the arm 31 will be removed and replaced by a paper guide shoe 53. An aperture provided in this shoe receives the stub shaft 33 instead of the axle of the sheet flattening roller. A shoe 54 corresponding to the shoe 53 is illustrated in Figure 3 as mounted on the arm 25 carrying the sheet flattening roller 28.

If desired, an extension 55 may be provided on the arm 31 extending from the bearing collar 32 toward the discharge end of the machine 10 and a counter-weight 56 may be mounted on this arm extension for adjustment longitudinally of the latter to control the action of the spring 52 on the disc 35.

With the above described simple attachment sheets issuing from the machine can be marked at intervals of a predetermined number of sheets, as indicated at 60, so that, as the sheets leave the machine they can be arranged in piles or stacks with a predetermined number of sheets in each pile or stack.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In combination, a sheet folding machine having a horizontal table, a horizontal endless conveyor extending along the table substantially in the plane of the table, a shaft extending across the table and across the conveyor, means mounting said shaft on the table in upwardly spaced relation to the table and to said conveyor, means connected to said conveyor for moving folded sheets on the conveyor toward one end of the table with the folds of succeeding sheets projecting upwardly from the conveyor, at least one roller arm pivoted on said shaft and having a sheet flattening roller at the side of said shaft remote from said one end of the table, another arm pivoted on said shaft and having a portion positioned at the side of said shaft adjacent to said one end of the table, a stubshaft on said portion of said other arm extending parallel to said shaft, a marking disc journaled on said stubshaft, said disc having circumferentially spaced teeth having edges arranged to be engaged by folds of sheets advanced by the conveyor toward said one end of the table whereby the disc is rotated on said stubshaft with the periphery of said disc bearing upon the sheets, and a marking pencil mounted on said disc in line with one of the said tooth edges for marking a sheet engaging said one edge.

2. In a marking attachment for a sheet folding

machine wherein the sheets are advanced in overlapped relation and with folds of succeeding sheets projecting upwardly from the sheets, a shaft adapted to be mounted across the machine and above the sheets, an arm pivoted on said shaft and extending radially therefrom, a marking disc journalled on said arm with its axis parallel to said shaft, and with its periphery bearing upon sheets on the machine, said disc having peripheral and circumferentially spaced teeth having edges arranged to be engaged by folds of succeeding sheets so that advancement of the sheets serves to rotate the disc, and a marking pencil on the disc in line with one of said

tooth edges for marking a sheet fold as such fold comes into engagement with said one tooth edge.

KENNETH A. WAGNER.
